DESIGN FOR A PATRIOTIC BADGE

Ray M. Mason, Lemont, Ill.

Application August 13, 1942, Serial No. 107,931

Term of patent 7 years

To all whom it may concern:

Be it known that I, Ray M. Mason, a citizen of the United States of America, residing at Lemont, county of Cook, and State of Illinois, have invented a new, original, and ornamental Design for a Patriotic Badge, of which the following is a specification, reference being had to the accompanying drawing, forming a part thereof, wherein:

I claim:

The ornamental design for a patriotic badge, as shown.

RAY M. MASON.
